Patented Mar. 22, 1921.

INVENTOR
FRANK O. WHITE,
by Arthur C. Eckert ATTORNEY.

UNITED STATES PATENT OFFICE.

FRANK O. WHITE, OF ST. LOUIS, MISSOURI.

VENTILATED FURNITURE.

1,372,057.

Specification of Letters Patent. Patented Mar. 22, 1921.

Application filed August 10, 1920. Serial No. 402,680.

To all whom it may concern:

Be it known that I, FRANK O. WHITE, a citizen of the United States of America, residing at St. Louis, State of Missouri, have 5 invented certain new and useful Improvements in Ventilated Furniture, of which the following is a specification.

The object of my invention is to fabricate a seat and back for furniture which will be 10 aerated, prevent the adhering of the user's clothing to the back of chairs, lounges, etc., in warm weather. A further object is to make the seat and seat element selectively detachable and to make the back and back 15 element selectively detachable.

In the conventional seat, the user in hot weather, due to perspiration, becomes very uncomfortable, particularly where he is compelled to remain in one seat for a considerable 20 length of time. An automobile driver, particularly where the limits of his bodily movements are small and where he drives for hours continually, becomes very uncomfortable in hot weather, owing to the lack of 25 air circulation in and around the seat and back.

My purpose is accomplished by providing an air space immediately under the seat and back whereby the air can pass, as well as a 30 perforated member, as cane or leather by which the air may pass from the air space to the person of the user.

Since it is necessary to upholster or cover the seat element and back element entirely 35 in order to prevent the chafing of the seat and back on which my device is used, it is desirable to have these elements detachably secured to the seat and back of my device.

With the above and other objects in view, 40 my invention has relation to certain novel features of construction and operation, examples of which are described in the following specifications and illustrated in the accompanying drawings in which—

45 Figure 1 is a plan of the seat element of my device.

Fig. 2 is a fragmental sectional elevation of my seat and back taken along the line 2—2 of Fig. 1.

50 Fig. 3 is an enlarged fragmental sectional elevation of a portion of Fig. 2 showing the attachable means between the seat element and the seat.

Fig. 4 is a front elevation of my seat ele-

ment looking in the direction of the arrow 55 in Fig. 1.

Numerals 5 designates the seat element having the upward curled lateral edges 6 bent as shown in Fig. 4.

Numerals 7 designates a slot in element 5. 60 A key hole slot 9 is cut in the tongue 8. The seat element 5 is covered with cloth 10: the screw 11 is secured by frictional engagement to the seat 12 shown at 13 having its head 14 held in spaced relationship with the lower 65 surface of the seat 12.

Numerals 15 designates the cane portion of the seat, 16 a leaf spring secured to the seat element 5 by means of the rivet 17. This structure is duplicated in each one of the 70 interlocking means. In order to position the seat in spaced relationship with the seat element and to lock it in that position the screw heads 14 positioned in the enlarged portion of the key hole slots 9 are pushed 75 into the channel portion of the key hole slots 9. The springs 16 are of such length that when the screws 11 arrive at the end of the slots 9, they take the position shown in Fig. 3 thereby preventing disassociation of 80 the seat and seat element. In order to remove the seat element it is only necessary to compress the springs 16 and reverse the recited operations.

Numerals 17 designates a back element and 85 18 a back which are similarly detachably secured to each other in spaced relationship.

Numerals 19 designates the spring which secures the seat element to the back element.

What I claim and mean to secure by Letters Patent is:

In ventilated furniture a seat element having slots cut therein and tongues stamped and bent therefrom, said tongues having key hole slots formed therein, a seat, a screw, 95 said screw secured in frictional engagement in said seat so as to position the head of said screw in spaced relationship with the lower surface of said seat so that said tongue by means of its key hole slot may be detachably 100 secured to said screw, a spring, said spring secured to said base plate so as to lock said screw in the key hole slot of said tongue in certain relative positions of said screw and said tongue.

105 In testimony whereof I affix my signature.

FRANK O. WHITE.
